UNITED STATES PATENT OFFICE.

GEORGE P. SPENCER, OF WATERTOWN, NEW YORK.

DESIGN FOR A COLLAR-BUTTONER.

SPECIFICATION forming part of Design No. 32,524, dated April 17, 1900.

Application filed March 14, 1900. Serial No. 8,676. Term of patent 14 years.

To all whom it may concern:

Be it known that I, GEORGE P. SPENCER, a citizen of the United States, residing at Watertown, in the county of Jefferson, State of New York, have invented and produced a new and original Design for Collar-Buttoners, of which the following is a specification, reference being had to the accompanying drawing, forming a part thereof, in which I show a view of the device complete.

As shown in the drawing, the leading or material feature of my design consists of a piece of steel wire *a*, bent semi-elliptically centrally, as shown at *b*, having one end *c* terminating to form a handle and the other end bent to form a loop *d*. The loop *d* has one end bent to form a recess *e*, in which the collar-button is gripped after the loop *d* has been passed through the buttonhole of the

collar. The opposite end of the loop *d* is bent 20 with a curve, as shown at *e'*, so as to allow it to pass freely through the buttonhole in the collar. I also force the part of the loop forming the eye *e* slightly out of alignment with the body of the buttoner, so as to more readily 25 grip the collar-button.

Having described my invention, what I claim, and desire to secure by Letters Patent, is—

The design for a collar-buttoner, as herein 30 shown and described.

In witness whereof I have hereunto set my hand this 28th day of February, 1900.

GEORGE P. SPENCER.
